UNITED STATES PATENT OFFICE

2,096,889

WATER BOWL HANGER

Martin B. Evenson, Arlington, Iowa

Application October 16, 1936, Serial No. 106,017

4 Claims. (Cl. 138—25)

As is well known, when it is desired to pump water from a pump through a pipe to a tank or other storage receptacle, there is used what is commonly known in the art a water bowl to which one end of the pipe or hose is connected. This water bowl is suspended from the faucet or nozzle of the pump and an object of the present invention is to provide improved means for suspending the water bowl from said faucet or nozzle.

Generally such a water bowl has associated therewith in a relatively loose manner a ring equipped with a splash shield, which ring often settles in the bottom of the bowl and becomes frozen therein with the result that it is difficult to remove the same from the bowl.

My invention has as an object therefor the provision of a hanger which will also serve to prevent the splash ring or shield from settling in the bottom of the tank and which will at the same time facilitate the raising of the ring or shield to proper position at the top of the bowl.

The invention together with its objects and advantages will be best understood from a study of the following description taken in connection with the accompanying drawings wherein:

Figure 1 is a side elevational view illustrating the application of the invention.

Figure 2 is a horizontal sectional view taken substantially on the line 2—2 of Figure 3.

Figure 3 is a sectional view taken substantially on the line 3—3 of Figure 2.

Figure 4 is an elevational view of the hanger.

Figure 5 is a sectional view taken substantially on the line 5—5 of Figure 4.

Referring to the drawings by reference numerals it will be seen that 5 indicates generally a hand pump and 6 the nozzle thereof. The nozzle 6 is provided with a horn or hook 7 in a conventional manner.

The water bowl is indicated generally by the reference numeral 8 and is provided with an outlet neck extending from the bottom thereof and indicated by the reference numeral 9. The neck 9 is adapted to have coupled thereto as at 10 one end of a hose or pipe 11 that is used for conveying the water pumped into the bowl to a storage tank or the like.

50 The bowl 8 is also provided with a splash guard or shield equipped ring 12 that fits within the bowl and is provided at its lower edge with an outstanding annular flange 13 that is adapted to engage the inturned flange 14 provided at the upper edge of the bowl. For a portion of its cir-

cumference the ring 12 is provided with an up-standing guard or shield piece 15.

The improved hanger is indicated by the reference numeral 16 and comprises, in the preferred embodiment thereof, a substantially U-shaped member 17 the legs of which at their terminals are provided with outstanding lugs or flanges 18. Adjacent the flanged ends 18 said legs of the U-shaped member 17 are provided with openings 19 through the medium of which and cotter pins or the like 20 the legs of the member 17 are pivoted to the shield 15 adjacent the respective free ends of the shield.

The U-shaped member 17 has its closed end curved and riveted, as at 21 or otherwise secured, to the curved closed end 22 of a substantially U-shaped handle member 23.

The free ends of the U-shaped member 23 are apertured to receive a bolt or rivet 24 that extends axially through a hand grip 25 and serves to secure the grip in position at the open end of the member 23.

From the above, it will be seen that the lugs or flanges 18 will serve to engage the flange 14 of the bowl 8 in a manner to limit the downward movement of the ring 12 relative to the bowl thus preventing the ring from dropping into the bottom of the bowl.

For suspending the bowl 8 from the nozzle or faucet 6 of the pump 5, the member 17 is placed in a position straddling the nozzle with the closed end of the member 17 engaging behind the hook or horn 7 as shown in Figure 1. With the hanger thus engaged with the ring 12 and the nozzle 6, said hanger will serve adequately for suspending the bowl 8 from the nozzle 6 and in a position to receive water discharging therefrom incidental to the operation of the pump 5.

It is thought that a clear understanding of the construction, utility and advantages of an invention of the character described will be had without a more detailed description thereof.

Having thus described the invention, what is claimed is:

1. In combination with a water bowl having a splash shield equipped ring loosely fitting therein and interengaging flanges on the wall of the bowl and on the ring for limiting outward movement of the ring relative to the bowl; a hanger member comprising a handle part having a substantially U-shaped member secured thereto, said U-shaped member having the legs thereof straddling the shield part of said ring and pivoted to said shield part adjacent the respective opposite

ends of said shield part, said legs of the U-shaped member at the pivoted ends thereof being also provided with outstanding stop flanges for engaging the flange of the bowl to limit inward movement of the ring relative to the bowl.

5 2. In combination with a ring adapted to be fitted within a water bowl and characterized by a stop flange for engaging the flange of the water bowl and an integral semicylindrical splash shield, a hanger member comprising a substantially U-shaped part having the legs thereof pivoted to the splash shield adjacent the respective opposite ends of said shield and stop lugs integral with the pivoted ends of the legs of said

10 15 3. In combination with a ring adapted to be fitted within a water bowl and characterized by a stop flange for engaging the flange of the water bowl and an integral semicylindrical splash shield, a hanger member comprising a substantially U-shaped part having the legs thereof pivoted to the splash shield adjacent the respec-

20 tive opposite ends of said shield and stop lugs integral with the pivoted ends of the legs of said U-shaped member, said U-shaped member being adapted to straddle the faucet of a pump with the closed end of the U-shaped member engaging the horn of the pump faucet.

4. In combination with a ring adapted to be fitted within a water bowl and characterized by a stop flange for engaging the flange of the water bowl and an integral semicylindrical splash shield; a hanger member comprising a substantially U-shaped part having the legs thereof pivoted to the splash shield adjacent the respective opposite ends of said shield and stop lugs integral with the pivoted ends of the legs of said U-shaped member, and a second U-shaped member secured at the closed end of the U to the closed end of the first named U, and a hand grip secured between the free end of the leg of the second U-shaped member.
